COMBINATION TELEVISION LAMP, CONVERTER, AND VASE

Charles F. Fenton, New York, N. Y.

Application May 13, 1954, Serial No. 30,471

Term of patent 7 years

(Cl. D48—28)

FIG. 1

FIG. 2

FIG. 3

To all whom it may concern:

Be it known that I, Charles F. Fenton, a citizen of Yugoslavia, residing at Long Island, New York, county of Queens, and State of New York, have invented a new, original, and ornamental Design for a Combination Television Lamp, Converter, and Vase, of which the following is a specification, reference being had to the accompanying drawing, forming part thereof.

Fig. 1 is a front perspective view of a combination television lamp, converter, and vase showing my new design;

Fig. 2 is a plan view thereof; and

Fig. 3 is a rear perspective view thereof.

I claim:

The ornamental design for a combination television lamp, converter, and vase, substantially as shown.
